UNITED STATES PATENT OFFICE.

EUGENE M. WEAVER, OF NEW YORK, N. Y.

DRAWBRIDGE RAIL-LOCK.

No. 853,611.

Specification of Letters Patent.

Patented May 14, 1907.

Application filed February 21, 1907. Serial No. 358,581.

To all whom it may concern:

Be it known that I, EUGENE MARR WEAVER, a citizen of the United States, residing on Woodhaven avenue, Ozone Park, in the county of Queens, city and State of New York, have invented certain new and useful Improvements in Track End Adjustments for Drawbridges, which I call a "Drawbridge Rail-Lock," for use on railroads, of which the following is a specification.

My invention relates to certain new and useful improvements in fastening the pivotal end drawbridge rail sections to the drawbridge proper. It is applied to the ends of the drawbridge underneath the movable rails. The movable rails on a drawbridge are those rails which make up the tracks on the ends of drawbridges, and called above "pivotal end drawbridge rail sections." The ends of the rails on the pivotal end drawbridge rail sections extend over on to the solid road bed. This is for the purpose of making a firm track joint. When the drawbridge is to be swung open these rails must be lifted in order to clear the rails on the solid road bed while the bridge is in the act of turning. These rails are from fourteen to twenty feet long, more or less, that is, the pivotal end drawbridge rail sections.

It is vitally necessary to the prevention of accidents that the pivotal end drawbridge rail sections be absolutely fastened and that every part of the rails of said pivotal end drawbridge rail sections be present after the drawbridge has been swung open for passing craft. The universal method of fastening the pivotal end drawbridge rail sections on the ends of the drawbridges is accomplished by a single bolt lock. This single bolt lock is all that fastens the pivotal end drawbridge rail section for a distance of from fourteen to twenty feet, beginning to measure from the end of the drawbridge.

One important point in my improvement is to fasten the pivotal end drawbridge rail section every two feet more or less apart both before and after the drawbridge has been opened and swung back into place, ready to permit a train to pass over it. After a drawbridge has been opened and closed again, it is possible that several feet of the rails of the pivotal end drawbridge rail sections may be missing, being broken by jarring or struck by passing craft or otherwise, and the remaining

rails of the pivotal end drawbridge rail sections would allow the drawbridge to be locked and signals to be cleared, thereby sending the train over an imperfect track. With my device attached this cannot happen. So, another important point is that with my device attached every part of the rails of the pivotal end drawbridge rail sections must be present or else the drawbridge cannot be locked and signals cannot be cleared.

A still further important point in my improvement is that it makes the pivotal end drawbridge rail sections on all drawbridges to which it may be applied, as secure as the spiking of the rails upon the solid road bed.

A still further important point is that I operate my improvement with one lever. If however occasion calls for it I may operate with more than one lever. I do not confine myself to one lever.

General statement of the objects and nature of my invention.—The objects of my invention are:

First—To compel all the pivotal end drawbridge rail sections on the ends of drawbridges to be in their proper and safe position before the drawbridge can be locked and the signal given for the train to pass over, after the said drawbridge has been opened for passing craft or other purpose. Every part of the rails of the pivotal end drawbridge rail sections must be in proper and absolutely safe position when the bridge is locked or not any of the remaining rails of the said pivotal end drawbridge rail sections can be fastened.

Second—Another object of my invention is to relate my drawbridge rail lock to the signal protecting the drawbridge, so that the signal cannot possibly be cleared until every part of the rails of the pivotal end drawbridge rail sections is in an absolutely proper and safe position for a passing train.

Third—Another and very important object of my invention is that it forms a fastening for the pivotal end drawbridge rail sections every two feet more or less, equivalent to that of spiking upon ties on the solid road bed.

Fourth—A still further object is that the entire combination used for fastening and unfastening the pivotal end drawbridge rail sections of the drawbridge, including both ends of the bridge, from one to a four track drawbridge or more, is accomplished by one

lever, that same lever thrown one way will fasten all the pivotal end drawbridge rail sections and reversed it will unfasten them.

Brief description of the several views of drawings.—I accomplish the stated objects by constructing and associating the elements as illustrated in the accompanying drawings of which

Figure 1 represents the sectional view of the pivotal end drawbridge rail sections of the drawbridge and a detail view of my invention as applied to the rails of the pivotal end drawbridge rail section. Fig. 2 shows the rotary locks side view, said locks being a part of my invention. Fig. 3 shows the plan of the drawbridge and its connection to abutments, also the general plan top view of the application of my invention. Fig. 3 also shows the application of my invention in relation to the signals protecting the drawbridge. Fig. 4 is a sectional view of my invention showing how it is connected with the connection rod, said connection rod being controlled by the one lever that operates the entire mechanism of my invention. This operating lever is shown in Fig. 3.

Detail description of drawings.—Fig. 1 represents the sectional view of the pivotal end drawbridge rail section and a detail view of my invention. *a.* shows the pivotal end drawbridge rail section in its normal position resting in an iron channel *c.* This iron channel *c.* is as long as the pivotal end drawbridge rail section, and is used as a reinforcement to the pivotal end drawbridge rail section, as the rail rests down into it when the said pivotal end drawbridge rail section is in its proper position. The pivotal end drawbridge rail section in this Fig. 1 is held in position by the dogs *b. b.*, these dogs in turn are locked by the rotary lock *d. d.*, said rotary lock being attached to the shaft *e.*, said shaft *e.* is indicated in Fig. 2.

Fig. 2 shows the rotary lock *d.* side view, together with the end view of shaft *e.* and edge view of dog *b.*, and side view of part of the rail of the pivotal end drawbridge rail section *a.* It will be seen in this Fig. 2 how the dog *b.* is held in its locked position by the rotary lock *d.*

Fig. 3 shows the plan of the drawbridge and its connection to abutments, also the general plan, top view of the application of my invention. It also shows the application of my invention in relation to the signals protecting the drawbridge. *a.* is the top view of the pivotal end drawbridge rail section indicated *a.* in Fig. 1. *b. b.* is a top view of the dogs indicated *b. b.* in Fig. 1. *e.* is the top view of the shaft indicated *e.* in Figs. 1 and 2. As is readily seen on drawing Fig. 3, the dogs *b. b.* can be placed two feet apart more or less, from point *f.* to point *g.* which is the whole length of the pivotal end drawbridge rail sections on the end of the draw-

bridge. At present this same distance of pivotal end drawbridge rail section is held only by the single bolt lock. As seen on drawing Fig. 1 the dogs *b. b.* clamp the rail of the pivotal end drawbridge rail section on the bottom flange of said rail, and lock the said rail into the iron channel *c.* Fig. 1. This is one of the principal features of my invention, as the rails of the pivotal end drawbridge rail sections with my device are fastened with the dogs *b. b.* Fig. 1 every two feet apart, more or less, whereas on all other drawbridges the only fastening for the pivotal end drawbridge rail sections is the single bolt lock, and this single bolt lock is supposed to fasten the pivotal end drawbridge rail section for a distance of from fourteen to twenty feet, measuring in from the end of the drawbridge. *h.* in Fig. 3 shows the connection rod, top view, bringing the operation of all the shafts *e.* to the control of the one lever marked *i.*

Fig. 4 is a sectional view of my invention showing how the rotary lock *d. d.* Fig. 2 on shaft *e.* Figs. 1 and 2, locks the dog *b. b.* Fig. 1, said dog *b. b.* connected with the connection rod *h.* Fig. 3.

How to operate.—To operate my device a man sets signal *k.* Fig. 3 by throwing the lever *l.* Fig. 3. This same throw of the lever *l.* unlocks the connection rod *h.* Fig. 3 at the point *m.* Fig. 3. At this point the connection rod *h.* Fig. 3 terminates and is there locked by the rod which operates the signal protecting the drawbridge, so that before anything can be done to effect the lifting of the pivotal end drawbridge rail sections or the opening of the drawbridge, this signal must be set to danger. Throwing the signal lever *l.* Fig. 3 unlocks the end of the connection rod *h.* Fig. 3 at point *m.* and permits the operator to then throw lever *i.* Fig. 3 which lever unlocks all the dogs *b. b.* Fig. 1. Pivotal end drawbridge rail sections are then ready for lifting and the drawbridge ready for opening. As the operator throws lever *i.* Fig. 3 he thereby releases all the dogs *b. b.* Fig. 1 from the bottom of the flange of the rails of the pivotal end drawbridge rail sections on all tracks, allowing said pivotal end drawbridge rail sections to be lifted. As the pivotal end drawbridge rail sections are lifted the dogs *b. b.* Fig. 1 which rotate on center pins *n.* Fig. 1 are thrown back as indicated in the dotted lines Fig. 1., and are thus held back by gravity far enough to allow the rails of the pivotal end drawbridge rail sections to pass out as indicated by *o.* dotted lines Fig. 1. The pivotal end drawbridge rail sections thus lifted, the drawbridge is ready for turning or raising. After the drawbridge is swung back or lowered into place as the case may be, then comes the closing of my device. Immediately after the drawbridge itself is swung back into normal position the pivotal end drawbridge rail section on the ends of the drawbridge are

lowered. As they are in the act of lowering, the bottom flange of the rail of the pivotal end drawbridge rail section engage the dogs *b. b.* Fig. 1 shown in the dotted lines *p. p.* and 5 rotate the said dogs to their normal position, such normal position is shown by the heavy lines of the dogs marked *b. b.* Fig. 1. The operator then restores his lever *i.* Fig. 3. In 10 restoring this lever, said lever being attached to the connection rod *h.* Fig. 3., and the said connection rod *h.* Fig. 3 being in turn attached to all the shafts *e.* Fig. 2., he thereby 15 engages rotary locks *d. d.* Fig. 2 into the dogs *b. b.* Fig. 1 thereby locking and fastening all 20 the dogs onto all the rails of the pivotal end drawbridge rail sections. If any one or more of the dogs should not be in their normal position due to any piece of any of the rails of the pivotal end drawbridge rail sections 25 being absent, or of any of the said rails not being down in their proper place the entire mechanism would be inoperative which would positively prevent the operator from clearing his signals, because the connection 30 rod would not complete its stroke at the point *m.* Fig. 3 for when the connection rod completes its stroke lever *l.* Fig. 3 can be restored to its normal position, which clears signals and signals cannot be cleared otherwise.

Having thus described my invention and explained the manner of its operation, what I claim as new and useful and desire to secure by Letters Patent is

35 1. In track end adjustments for drawbridges with pivotal end drawbridge rail sections, the combination with a drawbridge and cast steel dogs and rotary locks which lock said cast steel dogs and mechanism for 40 operating said cast steel dogs and locks,

whereby the pivotal end drawbridge rail sections may be fastened securely to the said drawbridge.

2. In track end adjustments for drawbridges with pivotal end drawbridge rail sections, the combination with a drawbridge and cast steel dogs and rotary locks which lock said cast steel dogs and mechanism for operating said cast steel dogs, whereby every portion of all of the rails of the pivotal end drawbridge rail sections must be present and in absolutely safe position fastened securely to said drawbridge before the signal protecting the said drawbridge can be cleared for the train to pass over said drawbridge.

3. In track end adjustments for drawbridges with pivotal end drawbridge rail sections, the combination with a drawbridge and cast steel dogs and rotary locks which lock said cast steel dogs and mechanism for operating the said cast steel dogs whereby the rails of the said pivotal end drawbridge rail sections are fastened equally as rigid as the rails upon the solid road bed, said cast steel dogs being placed substantially two feet apart.

4. In track end adjustments for drawbridges with pivotal end drawbridge rail sections, the combination with a drawbridge and cast steel dogs and rotary locks which lock said cast steel dogs, and mechanism for operating the said cast steel dogs and rotary locks, whereby all of the rotary locks which lock said cast steel dogs are operated by one lever.
